UNITED STATES PATENT OFFICE.

GRAHAM C. PARISH, OF LAKE KATRINE, NEW YORK.

RETAINING MEANS FOR RATCHET PINS.

Application filed December 3, 1921. Serial No. 519,717.

To all whom it may concern:

Be it known that I, GRAHAM C. PARISH, a citizen of the United States, residing at Lake Katrine, in the county of Ulster and State of New York, have invented certain new and useful Improvements in Retaining Means for Ratchet Pins, of which the following is a specification, reference being had therein to the accompanying drawings, which form a part thereof.

My invention relates to retaining means for ratchet pins, and more particularly to a device for use in connection with a hollow pulley secured to the shaft of an internal combustion engine by means of a ratchet pin, said pulley being used as a driving pulley for a fan belt for circulating air about a radiator through which the water used in cooling the engine, is circulated.

The combined pulley and ratchet mechanism with which my retaining means is adapted to be combined, is very extensively used in a certain well known type of automobile, the common practice being to provide a pulley having diametrically opposite openings through the face thereof to facilitate the mounting and removal of same, the pin itself being retained within the pulley by means of cotterpins passing through opening in the pin and projecting beyond same so as to engage the inner wall of the pulley.

It is the common experience in devices of the character immediately above referred to, for the cotterpins to wear and become separated from the ratchet pin, thus permitting said ratchet pin to escape through the opening in the pulley and either become bent or broken in such a manner as to jam the mechanism adjacent thereto, and break the driving belt or force it from the pulley, or to break off within the pulley.

When a pin projects beyond the pulley and is bent out of form, it is frequently necessary to remove the entire radiator structure in order to have access to the pulley because of the small space about this pulley. This small space between the pulley and the radiator also makes the use of tools about the ratchet pin both inconvenient and difficult.

With the above conditions in mind, I have provided a retaining means which

may be quickly mounted in, and removed from, the pulley and in a relation to the ratchet pin which will avoid all possibility of the escape of the pin through the holes in the pulley, said means not being subject to likelihood of displacement while in use, and being so constructed as to avoid any such wear thereon as would make the means inoperative to an extent to permit the escape of the pin.

The retaining means is so constructed that it may be readily attached to, and removed from, the pulley with the use of one hand in the contracted space between the pulley and the radiator, thus leaving the other hand free to control the ratchet pin while the retaining means is being positioned. No tools of any kind are required in mounting and removing the retaining means, and the positioning of this means within the pulley will, under all conditions, be sufficiently permanent to avoid likelihood of its escape, and thus it affords a positive safeguard against the escape of the ratchet pin and the complete disabling of a car thereby.

The invention consists primarily in retaining means for ratchet pins embodying therein the combination with a hollow pulley having a hub adapted to fit the shaft of an internal combustion engine adjacent an opening therethrough, the face of said pulley and said hub having diametrically opposite aligned openings, and a pin adapted to pass through said openings and project between said hub and the inner wall of the pulley face to connect said pulley with said shaft and form ratchet teeth upon opposite sides of said hub, of a spring member adapted to be bent to semi-circular form to project across said openings in the face of the pulley and have pivotal movement about an axis substantially concentric with that of said pin to facilitate the mounting and removal of the member adjacent the inner wall of the pulley face; and in such other novel features of construction and combination of parts as are hereinafter set forth and described, and more particularly pointed out in the claims hereto appended.

Referring to the drawings, Fig. 1 is a perspective view of retaining

means embodying my invention shown combined with a hollow pulley and its associated ratchet pin;

Fig. 2 is a vertical section therethrough with the shaft shown in elevation;

Fig. 3 is a perspective view of the semi-circular retaining spring removed from the pulley;

Fig. 4 is a view of another form of the invention; and

Figs. 5 and 6 illustrate still another form thereof.

Like letters refer to like parts throughout the several views.

In the accompanying drawings, I have shown at *a* a hollow pulley of the usual construction having an overhung face *b* and a hub *c* concentric with and within said face *b*. The inner wall of the face *b* is substantially parallel with the cylindrical hub *c*, said pulley *a* and its face *b* being without flanges. The formation of the contact face of the pulley is immaterial to the present invention, since it may or may not have 25 a crown, as desired.

The hub *c* is adapted to have a loose sliding fit upon the crank shaft *d* of an internal combustion engine, which shaft has a transverse opening *e* therethrough adapted to receive a pin *f*.

The pulley face *b* and its hub *c* have diametrically opposite aligned openings therethrough of a diameter to permit the pin *f* to be passed freely therethrough and passed 35 through the opening *e* of said shaft, said pin being of a length to pass through said shaft and said hub and project into the space between the hub and the pulley face *b* so as to connect said pulley with said shaft and form 40 ratchet teeth upon opposite sides of said hub adapted to be engaged by the ordinary clutch member of an internal combustion engine starting crank.

The open end of the pulley while in use 45 is presented toward, and positioned closely adjacent, the radiator of an automobile, which has led to the difficulty of effecting repairs in the event of the breakage of the pin or of its projection through one of the 50 openings in the pulley face *b* so that by impact with other parts about the engine, it becomes bent or jammed so that it may be removed only by means of machinery or tools.

To secure the desired permanency in the 55 relation of the pin *f* with the pulley, while at the same time permitting the expeditious removal of a broken pin and the substitution of a new one therefor, I provide a flexible 60 spring member *g* adapted to be readily brought to a semi-circular form, this member being of a length, so that when it is brought to this form, it will project across the diametrically opposite openings in the 65 pulley face *b* and engage the ends of the pin

f in a manner to prevent the movement of said pin through either of said openings. By using a spring member of the character described, the ends thereof will have a bearing against substantially diametrically opposite points either upon the inner wall of the pulley face *b* or upon the pin *f* so as to permit the spring, when it has been flexed and formed, to have pivotal movement substantially concentrically with the axis of the 70 pin *f*. This greatly facilitates the mounting of said spring member within said pulley and its removal therefrom in the event of the breakage of the pin. It is unnecessary to provide for the removal of the pin in the 80 event of its escaping through an opening in said pulley face, since this cannot occur when the spring member *g* is used.

While the flexibility of the spring member *g* will tend to hold it firmly in place, the retaining means is so constructed that the ends of the spring member will have a permanent relation to the ends of the pin *f*, thus preventing circumferential creepage of the spring member so as to expose one of the 90 openings in the pulley face. This characteristic of the invention may be secured either by a detachable connection between the spring member *g* and the pulley face *b* through the mediums of the openings there- 95 through, or by means of a detachable connection between said spring member and the ends of the ratchet pin *f*.

For convenience in mounting the spring member *g* in, and removing it from, the pulley, I prefer to employ the former expedient, such a construction being shown in Figs. 1 to 3 of the drawings. In this form of the invention, I provide the spring member *g*, which is a strip of flat wire, adjacent each 100 end thereof with a rivet *h*, the upset portion *h'* of which is of relatively smaller diameter than the openings in the pulley face *b*, and the head of which is rounded as shown in Figs. 2 and 3, to give a large 110 wear surface for the pin *f*.

The ends of the member *g* are bent slightly at an angle as shown in Fig. 3, at *i*, to facilitate the engagement of either end 11 of said member with the inner wall of the pulley, and minimize any tendency of the end of the member to bite against said wall during its pivotal movement.

Referring to Fig. 4 of the drawings, the construction is as heretofore described, except that instead of using a flat spring wire in producing the member *g*, I use a round spring wire strip, and instead of securing said member to the pulley *a* through the medium of the openings through the face *b* 12 thereof, I provide the pin *f* with transverse openings *f'* adjacent opposite ends thereof adapted to receive the ends of the member *g*. In this form of the invention, no wear surfaces are required, since the distance between 13

the openings f' will center the pin f in relation to the shaft d , any thrust of said pin radially of said shaft being against the tension of said spring member. One end of said spring member is turned slightly as shown at h^2 to facilitate the engagement of that end of the spring with an opening f' .

Referring to Figs. 5 and 6, the pin f is provided with grooves j adjacent the opposite ends thereof adapted to receive the slotted end g' of a spring member g corresponding in other respects with the form of spring member shown in Figs. 1 to 3. This form of the invention has exactly the same operative effect as that shown in Fig. 4, as to the centering of the pin, and the absence of the necessity of means forming a wear surface by reason thereof.

The mounting of the retaining member g in relation to the inner wall of the pulley face b and the pin f in the embodiments of my invention described, is effected in substantially the following manner:

Assuming that a pin f be broken, it is merely necessary to pass the hand between the pulley a and the radiator, and pull the spring member g outwardly of said pulley, the ends of said member having pivotal movement about an axis substantially concentric with that of the pin f . This may be done irrespective of the position of the pulley at the time, which is a matter of considerable importance, since it is not always possible to stop the engine with the axis of said pin in a vertical position.

When the spring has thus been pivotally turned, one end thereof may be flexed so as to disengage the upset end h' of the rivet h from the opening in the pulley face b in which it is seated, thus permitting a complete removal of said member g from the pulley, and uncovering both openings through the pulley face b . The pin may then be allowed to drop, or be moved, through the opening.

A new, or the same, spring member g is then used, the upset end h' of one of the rivets h being inserted in one of the openings of the face b upon the inside of the pulley, and a pin f dropped or passed through the aligned openings in the pulley face b , hub c and shaft d , until it rests upon the head of said rivet, whereupon the spring member g is flexed or brought to semi-circular form, and the free end thereof passed within the pulley until the upset end h' of the rivet enters the diametrically opposite opening in the pulley face b , whereupon said spring member is given a pivotal movement to bring it in its entirety within said pulley.

When so positioned, the flexibility inherent to said member g will hold it firmly in place, the upset ends h' of the rivets upon opposite ends thereof preventing any cir-

cumferential movement, or creepage, of said member. When the spring member g is thus formed, it will have a length of slightly more than 180° in arc, and will project across both openings, the bent ends 70 i preventing these ends biting into the inner wall of the pulley face b .

By having the upset ends h' of smaller diameter than the openings with which they co-operate, the member g may be used with pulleys of slightly different diameters, and greater facility is afforded in the handling of the retaining member.

The pulley a being free from any internal obstructions, it will be readily understood 80 that the member g may be readily mounted in, and removed from, the pulley structure, and will be retained in place solely by the flexibility inherent thereto.

In the form of the invention shown in 85 Fig. 4, the same procedure is followed as referred to above in connection with the form of the invention shown in Figs. 1 to 3, with the exception that the turned end of the member g will be inserted in one of the 90 openings f' before said member is given its semi-circular form, the pin f being allowed to move to the full extent permitted by the member g , before the opposite end of said member is passed through the opening f' 95 in the other end of said pin. When both ends of the member g have thus been assembled in the pulley structure, said member receives pivotal movement, the pin f turning therewith.

Referring now to the form of the invention shown in Figs. 5 and 6, the operation is the same as that described in connection with Fig. 4, with the exception that instead of passing the ends of a round wire through 105 openings in the pin f , the forked ends g' of the flat wire member g are fitted to the slotted portions j of said pin f , the frictional engagement of said ends with said pin causing the pin to turn with said member when 110 imparting pivotal movement thereto to bring it within the pulley.

In the forms of the invention shown in Figs. 4 to 6, the member g is not permitted a reflex action sufficient to engage the ends 115 thereof with the inner wall of the pulley face, as in the form of the invention shown in Figs. 1 to 3, the tension of said spring being relied upon to center the pin f and hold the ends thereof away from the openings in the pulley face b .

In all forms of the invention, the member g is subject to substantially no wear so that a replacement of the pin f will be required solely when in cranking the engine, this pin 125 breaks, a condition which cannot do any permanent injury to the machine, or prevent its being readily started by a mere substitution of a pin, which may be accomplished in a very short time.

The essential characteristic of my invention is the provision of a spring member *g* which may readily be assembled in, or combined with, a pulley structure of the type herein referred to, in replacing a broken pin *f*, said member engaging the ends of said pin in a manner to prevent displacement thereof radially of the shaft *d*, and being capable of being readily mounted within, and removed from, its operative relation to the pulley and to said pin without the use of tools.

The member *g* may be readily used in connection with any pulley of the type herein shown, it being the practice to sell said member *g* with a pin *f* separate and apart from the pulley so that an automobilist may carry a reserve supply of pins and spring members in a tool box, in order to be equipped to quickly remove a broken pin from the pulley and replace it with a new one, which may be done even by an unskilled driver.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is—

1. Retaining means for ratchet pins embodying therein the combination with a hollow pulley having a hub adapted to fit the shaft of an internal combustion engine adjacent an opening therethrough, the face of said pulley and said hub having diametrically opposite alined openings, and a pin adapted to pass through said openings and project between said hub and the inner wall of the pulley face to connect said pulley with said shaft and form ratchet teeth upon opposite sides of said hub, of a spring member adapted to be bent to semi-circular form to project across said openings in the face of the pulley and have pivotal movement about an axis substantially concentric with that of said pin to facilitate the mounting and removal of the member adjacent the inner wall of the pulley face.

2. Retaining means for ratchet pins embodying therein the combination with a hollow pulley having a hub adapted to fit the shaft of an internal combustion engine adjacent an opening therethrough, the face of said pulley and said hub having diametrically opposite alined openings, and a pin adapted to pass through said openings and project between said hub and the inner wall of the pulley face to connect said pulley with said shaft and form ratchet teeth upon opposite sides of said hub, of a spring member adapted to be bent to semi-circular form to project across said openings in the face of the pulley, and pro-

jections adjacent the opposite ends of said spring member adapted to enter the diametrically opposite openings through the pulley face, whereby said member is permitted to have pivotal movement about an axis substantially concentric with that of said pin to facilitate the mounting and removal of the member adjacent the inner wall of the pulley face.

3. Retaining means for ratchet pins embodying therein the combination with a hollow pulley having a hub adapted to fit the shaft of an internal combustion engine adjacent an opening therethrough, the face of said pulley and said hub having diametrically opposite alined openings, and a pin adapted to pass through said openings and project between said hub and the inner wall of the pulley face to connect said pulley with said shaft and form ratchet teeth upon opposite sides of said hub, of a spring member adapted to be bent to semi-circular form to project across said openings in the face of the pulley, and headed rivets carried adjacent the opposite ends of said spring member and having the upset portions thereof project from one side thereof so as to be adapted to enter the diametrically opposite openings through the pulley face, whereby said member is permitted to have pivotal movement about an axis substantially concentric with that of said pin to facilitate the mounting and removal of the member adjacent the inner wall of the pulley face, and said member will be relieved of wear adjacent said openings by the interposition of the rivet heads between same and the end of the pin.

4. Retaining means for ratchet pins embodying therein the combination with a hollow pulley having a hub adapted to fit the shaft of an internal combustion engine adjacent an opening therethrough, the face of said pulley and said hub having diametrically opposite alined openings, and a pin adapted to pass through said openings and project between said hub and the inner wall of the pulley face to connect said pulley with said shaft and form ratchet teeth upon opposite sides of said hub, of a spring member adapted to be bent to semi-circular form to project across said openings in the face of the pulley, and headed rivets carried adjacent the opposite ends of said spring member and having the upset portions thereof project from one side thereof so as to be adapted to enter the diametrically opposite openings through the pulley face, whereby said member is permitted to have pivotal movement about an axis substantially concentric with that of said pin to facilitate the mounting and removal of the member adjacent the inner wall of the pulley face, and said member will be relieved of wear adjacent said openings by the inter-

position of the rivet heads between same and the end of the pin, the upset ends of said rivets being of smaller diameter than said openings to adapt said member to 5 pulleys of varying diameters, and the ends of said member being bent at an angle from other portions thereof.

5. Retaining means for ratchet pins adapted for use in a pulley of the character 10 herein described, consisting of a flat spring metal strip adapted to be bent to semi-circular form, and a headed rivet passing

therethrough adjacent each end thereof, the upset portions of said rivets projecting beyond the surface thereof.

In witness whereof I have hereunto affixed my signature, in the presence of two subscribing witnesses, this 22d, day of Nov. 1921.
